(57) **CLAIM**

The ornamental design for a multi-direction socket, is as shown and described.

DESCRIPTION

FIG. 1 is a front right perspective view of a multi-direction socket showing my new design;

FIG. 2 is a front elevation view thereof;

FIG. 3 is a rear elevation view thereof;

FIG. 4 is a top plan view thereof;

FIG. 5 is a left side elevation view thereof;

FIG. 6 is a right side elevation view thereof; and,

FIG. 7 is a bottom plan view thereof.

The broken lines represent the portions of the design that form no part of the claim.
